SLICER

Florian B. Pedersen, Alameda, Calif.

Application April 29, 1938, Serial No. 205,057

3 Claims. (Cl. 30—116)

My invention relates to an improved device for slicing materials, such as cheese or butter; and the broad object of the invention is to provide a simple, hand operated slicing instrument having a guide roller for controlling the thickness of slice.

The invention possesses other objects and features of advantage, some of which, with the foregoing, will be set forth in the following description of my invention. It is to be understood that I do not limit myself to this disclosure of species of my invention, as I may adopt variant embodiments thereof within the scope of the claims.

Referring to the drawing:

Figure 1 is a perspective view of a slicer embodying the improvements of my invention; and

Figure 2 is a detail view showing an alternate construction for holding the cutting element.

Figure 3 is a perspective view showing a modified form of slicer embodying my invention.

In terms of broad inclusion, the slicer of my invention comprises a frame including a pair of arms having journal receiving sockets; a guide roller between the arms for engaging the surface of the material to be sliced; and journal means for the roller seated in the arm sockets. An elongated element is provided for cutting the material to be sliced, and is stretched between the arms to keep the element taut and to hold the journal means in the sockets. The axis of the guide roller is preferably inclined to the cutting element, and the roller is preferably conical and mounted for axial adjustment to vary the thickness of slice.

In greater detail, and referring to Figure 1 of the drawing, the slicer embodying my invention preferably comprises a one-piece frame of suitable material, such as wire, having a looped portion providing a handle 2, and having end portions diverging from the handle to provide a pair of spreader arms 3.

A taut cutting element 4 is provided at the ends of the arms, and is preferably a metal ribbon sharpened along one or both edges for slicing the material 6, such as cheese or butter. The ribbon is connected to the arms in any suitable manner, as by providing apertures 7 in the ribbon for engaging notched ends of the frame. This simple arrangement firmly holds the ribbon, but permits ready removal by pressing the arms together and slipping off the ribbon. An alternate fastening is shown in Figure 2, wherein the ends of the arms are slotted and provided with recesses 8 for receiving cross pins at the ends of the ribbon.

5 A guide roller 9 is positioned between the frame arms to engage the surface of the material being sliced, and is mounted on a rod or shaft 11 having pointed ends seated in journal sockets 12 provided in the frame arms intermediate the handle and cutting element. The journal means is held in the sockets by the taut cutting element 4 stretched between the ends of the arms. By this holding arrangement the construction of the device and its assembly is made very simple, since the parts are all held together by the taut cutting element.

10 In order to adjust the thickness of slice the roller 9 is preferably conical, and is slidably mounted on the shaft 11. One end of the shaft is spaced further from the cutting element than the other end to incline the roller axis; and this slant is such that the line of rolling contact is always parallel to the cutting element. By sliding the roller along its shaft the spacing between the roller and cutting element is varied to alter the thickness of slice. Since the line of rolling contact is parallel to the cutting element, there is no tendency for the roller to shift from a predetermined setting. If desired however suitable means may be provided for holding the roller in a selected position of adjustment.

15 As shown in Figure 1, the plane of cutting ribbon 4 is parallel to the surface of the material and to the forward path of the roller, so that the ribbon acts as a knife in slicing through the material.

20 Instead of the handle 2 lying in the plane of the arms, it may project forwardly as shown in Figure 3. In this case the arms 3 are bent downwardly at 13 to position the cutting element below the roller. This figure also shows an alternate form of cutting element comprising a fine wire 14 stretched taut across the ends of the frame arms. Cutting wire 14 is preferably fastened by simply placing the latter in slots 16 at the ends of the frame and clamping the cut portions together.

25 In both of the slicing instruments the act of grasping the handle and squeezing it does not tend to slacken the cutting element or unseat the shaft, but rather tends to further tension the element and more firmly hold the shaft.

I claim:

30 1. A slicer comprising a wire frame having an open loop portion providing a handle and having end portions providing arms having journal receiving sockets, each arm lying on the same side of the frame as the side of the loop from which the arm extends, a taut cutting element

connected between the arms, a guide roller between the arms and interposed between said cutting element and handle, and journal means for the roller seated in said sockets.

2. A slicer comprising a wire frame having an open loop portion providing a handle and having end portions providing arms having journal receiving sockets, each arm lying on the same side of the frame as the side of the loop from which the arm extends, said arms having portions extending transversely to the plane of the handle, a taut cutting element connected between the transversely extending portions of the arms, a guide roller between said transversely extending arm portions and interposed between said cut- 15

ting element and handle, and journal means for the roller seated in said sockets.

3. A slicer comprising a wire frame having an open loop portion providing a handle and having end portions providing arms having journal receiving sockets, each arm lying on the same side of the frame as the side of the loop from which the arm extends, a taut cutting element connected between the arms, a conical guide roller between the arms and interposed between said cutting element and handle on an axis angularly disposed to the element, and journal means for the roller seated in said sockets.

FLORIAN B. PEDERSEN.
